UNITED STATES PATENT OFFICE.

FREDERICK W. PARSONS, OF CLEVELAND, OHIO.

FIRE-PROTECTIVE SYSTEM.

Application filed October 17, 1923. Serial No. 669,016.

The present invention pertains to an improved system of lacing buildings and work-shops with fusible cables in connection with fire alarm or protective devices, the general object being to minimize the fire hazards and safeguard the buildings and the persons and property within the buildings, preferably using a flexible wire cable with a multiplicity of fusible bonds such as shown and described in my Letters Patent of the United States of America, No. 1,455,805, dated May 22, 1923.

In the accompanying drawings, Fig. 1 is a cross-section and perspective view of a building laced with a thermal control cable according to my present invention. Fig. 2 illustrates a short piece of control cable and a fusible bond therein. Figs. 3 and 4 are horizontal sectional views of buildings laced according to my present conception, an electrical signaling circuit being diagrammatically shown in connection with the fusible cable circuits.

My invention involves the use of a relatively long and flexible control element A having fusible links or bonds 2 at frequent intervals therein and stretched taut along the walls and ceilings, underneath or behind work benches, through or contiguous to storage places, etc., in the rooms of any building, and this fusible element is used in connection with a fire protecting device or system, such as an electric signaling system or alarm B, a fire door C, or a sprinkling device D, to operate them automatically upon the outbreak of a fire. The control element A which I prefer to use comprises a twisted wire cable approximately three-thirty seconds of an inch in diameter made in short sections with the wire strands 3 separably interlaid at the meeting ends of the respective sections and united and bonded together with relatively small and smooth bodies 4 of low fusing solder substantially as illustrated in Fig. 2.

In lacing a group of factory buildings, or a building having corridors and rooms, or partitioned sub-divisions, I find it advantageous and useful to provide a main control cable A and one or more branch control cables A' extending therefrom. These cables are supported to run freely around small pulleys or sheaves 5 mounted at suitably spaced intervals upon the ceiling, walls or other stationary parts within the building, and the main control cable A is preferably

in the form of a closed or endless loop to permit it to creep and shift under repeated testing operations which tests may be made several times daily in giving audible signals in starting and stopping work in a work-shop or plant.

The main cable A is stretched taut and maintained in that condition by means of a weight 6 having a supporting sheave 7 suspended in free-running engagement within a supplemental loop 8 in the endless cable A, and in Fig. 1, I show weight 6 arranged above and adapted to engage a pair of electrical contacts 9 to close an electrical signaling circuit B when the weight drops or is lowered, either by a parting of the cable A at any one of the fusible bonds 2, or by causing a slack or surrender in the otherwise taut cable. One or more supplemental loops 11 are formed in the main endless cable A at any point or place where it may be found desirable to run an extension control cable A' therefrom, and this extension cable A' may be short or relatively long and anchored, either permanently or detachably, to a fixed or movable part at some distant point or place inside or outside of the building.

In Fig. 1 I show the main control cable A extending in the form of an endless loop around sheaves 5 supported upon the ceiling and sidewalls of a building, and a short supplemental loop 11 is shown in the foreground at the left within which a sheave 12 is suspended and from which a branch cable A' extends downwardly and thence around a fixed sheave 13 parallelly with and beneath a work-bench 14. The end of branch cable A' is hooked to a leg of the bench and a detachable connection may be used or the cable may be permanently fastened at this end. Generally a detachable connection is employed to permit the branch cable A' to be detached and held in the hand and more or less slack given to the cable and a similar surrender permitted in the main loop or cable A whenever a test is to be made of the operativeness of the fire-alarm signal or the cables.

It should also be noted that a short loop 15 is formed in fusible branch cable A', within which a sheave 16 is reeved which has still another fusible branch cable A² extending therefrom downwardly through the floor of the building into a basement or store room, the second extension A² being stretched

horizontally beneath the floor and thence around a series of sheaves 17 circuitously between storage shelves or racks 18. The end of the second cable A² is detachably secured to a hook 19 upon a stationary part of the rack, and the fire-alarm signal and operativeness of the main cable A and the first branch A' and second extension A² may be readily tested by detaching cable A² from hook 19.

The endless main cable A is shown as stretched on circuitous lines lengthwise of the ceiling, and in practice any desired number of short loops 11 may be provided at intervals therein, or wherever it may be necessary or desirable to extend a fusible branch cable A' therefrom. To exemplify, in Fig. 1 I show two additional loops 11^a and 11^b, respectively, in main cable A, loop 11^a being reeved around a sheave 20 from which a short fusible cable A³ extends to and connects with a pivoted counterweighted latch 21 which is used to hold a gravity-closing fire-door C open under normal conditions. Loop 11^b is reeved around a sheave 23 from which a relatively long fusible control cable A⁴ extends downwardly to a fixed sheave 24, thence parallelly beneath a work table 25, thence around fixed sheaves 26 and downwardly through an opening in the floor into a furnace room, thence horizontally beneath the floor and upwardly around suitable sheaves into the work room again, and thence to a second work bench 27 where the terminal end of the cable is hooked or fastened to keep the cable taut. To denote the adaptiveness of the invention to a variety of conditions and needs, the branch cable A⁴ last described is also shown in Fig. 1 as provided with two short loops 28 and 29, respectively, reeved around separate sheaves or pulleys 30 and 31, having independent fusible control cables A⁵ and A⁶, respectively, extending therefrom to different points in the furnace room. Cable extension A⁵ is connected to the weighted end of a lever 32 which controls the opening of a valve for a sprinkling device D, and cable A⁶ extends into close proximity to the walls of a furnace F.

Upon the outbreak of a fire at any point or place within a short radius of any one of the multiplicity of low fusible joints or bonds 2 in main cable A or any one of its separate branches or extensions, A' to A⁶, respectively, a parting of the cable sections will take place immediately under the strain or tension imposed upon all the cables by weight 6, which weight is heavier than the other weights used in the train of connections at fire-door C and sprinkling device D. As a result, a fire-alarm signal is given by the electrical signaling apparatus B, which in actual practice is generally located outside of the building, or in a cen-

tral station more or less remote from the building. The signaling devices may be of any suitable kind, either electrically or mechanically operated.

In Fig. 3 I illustrate a plan of a building G, which may be an office building or a hospital, having a main corridor or hall 35, and a series of rooms 36 upon opposite sides of this hall. In lacing a building of this type with my invention the endless main cable A is stretched around sheaves within the hall, and an open loop 11 is formed within the cable opposite each room. A branch cable A² is then stretched circuitously in each room and connected to a sheave 37 having a free-running connection with the loop 11 in the hall opposite the corresponding room. When all the branch cables and the main cable are stretched taut by weight 6, suspended from a sheave within a loop in the main cable circuit, the weight is spaced apart from a switch represented diagrammatically by two electrical contacts 38-38 in an electrical signaling circuit 39. If the endless main cable is given enough slack to lower the weight and close the electrical circuit, an alarm or signal will be given, and this may be done either by creating a slack in one of the branch cables or by fusion of any single link or bond 2 in the main cable A or any one of the branch cables A².

In Fig. 4, I show two separate factory buildings H and H' respectively, having rooms therein laced with a series of fusible cables passing around sheaves mounted upon the ceiling or other part of the buildings. The main control cable A in building H is endless and held taut by a weight 40 suspended from a short loop 41 above a set of electrical contacts 42 in an electrical signaling circuit 43. A branch cable A' is laced to the walls or ceiling in the adjoining room and connected at one end to a pulley 44 which is engaged with a second short loop 45 in main cable A. Branch cable A' is also held taut by weight 40, the opposite end of the branch cable being anchored at 46 to a fixed part of the building. A second endless cable 47 is extended into another room from a short loop 48 in the taut branch cable A', a double pulley or coupling device 49 serving to connect loop 48 in free-running engagement with a short loop 50 in the endless branch cable 47, which is free to creep around its supporting sheaves 51 when tested, but normally held taut by weight 40. An endless primary cable and endless branch cables also make the system more responsive in action, especially when the cables are relatively long and are extended great distances from the base or place of beginning. The lacing of other rooms in the same building or other buildings is further exemplified in Fig. 4 by additional branch cables 52 and 53 connected with short loops 54 and 55 in

the endless branch cable 47. Branch cable 53 in building H', is shown as having a branch cable 56 of its own extended therefrom. Each and all of the cables in the system are held taut by the same weight 40, so that when any single bond fuses, the slack in the line will instantly cause operation of the signaling or protective devices as hereinbefore described.

10 Sheaves 5 which support cables A and A' are stationed in fixed positions upon the walls or other suitable supports within the building, but the sheaves to which the ends of the branch cables A' are connected are 15 supported only by the main cable and held in position by the branch cables until fusing occurs. For example, sheaves 12, 16, 20, 23, 30 and 31 are supported by and held in free running connection with the main cable.

20 What I claim, is:

1. A system of lacing buildings with fusible cables, comprising an endless main cable having a loop and fusible bonds therein, a branch cable having a loop and fusible bonds and connected to the loop in said main cable, an extension cable connected to the loop in said branch cable and a common tension device for all the cables.

2. A system of lacing buildings with fusible cables, comprising an endless main cable having fusible parting places therein and supported to permit creeping circuitously, and branch cables having fusible parting places therein and connected to sheaves reeved to and supported by said main cable.

3. A system of lacing buildings with fusible cables, comprising an endless main cable having fusible uniting ties therein, a tension device for said cable, a branch cable 40 having a sheave reeved to and supported by

said main cable, and means adapted to detachably anchor said branch cable under tension.

4. A system of lacing buildings with fusible cables, comprising an endless main cable having fusible bonds therein, a branch cable having fusible bonds and connected to and held under tension by said main cable, means adapted to place both the main cable and branch cable under the same tension, and means adapted to permit a temporary yield in said cables jointly for testing purposes.

5. A system of lacing buildings with fusible cables, comprising an endless cable 55 having fusible joints and a plurality of loops therein, a tension device having a sheave reeved to and supported by one of said loops, and a branch cable having a sheave reeved to and supported by another of said loops and provided with means adapted to connect it detachably to an anchorage.

6. A fire protective system of lacing buildings with fusible cables, comprising an endless main cable having fusible bonds at 65 intervals; means adapted to support said cable for endless travel; an extension cable connected to said main cable, having fusible bonds at intervals; and means adapted to place the main cable and extension cable under the same tension.

7. A fire protective system, comprising a plurality of endless cables having fusible portions at intervals therein, each endless cable being supported to permit creeping, 75 and means adapted to maintain a uniform tension on all of said endless cables.

In testimony whereof I affix my signature hereto.

FREDERICK W. PARSONS.
